ABSTRACT: A crusher tool for gyratory crushers comprising a stationary crushing ring and a rotary and tumbling crushing cone which on their opposed cooperating conical working surfaces are provided with a novel type of cooperating concentrically arranged annular projections and depressions, respectively. The annular projection on the crushing ring in cross section is rectangular with rounded corners and is adapted to enter into a correspondingly shaped annular depression formed in the crushing cone, except that the vertical flanks of the projection are spaced from the vertical walls of the depression in the crushing cone. The height of the annular projection on the crushing ring is at equal or greater than the depth of the associated annular depression in the crushing cone.

CRUSHER TOOL FOR GYRATORY CRUSHERS

The invention relates to crusher tools for gyratory crushers, consisting of a crushing cone and a crushing ring which have on their working faces interengaging, concentric prominences and depressions which form in axial section a tooth- or undulated-profile, whereby at any one time a tooth- or wave-front of one crushing member lies opposite a tooth- or wave-front space of the other crushing member.

At the comminution to final grain sizes of 5 to 25 mm., for many purposes of use predetermined requirements are made as to the grain form, as with blast-furnace-ready ore grains or fine-gravel grains or refined gravel grains for road- and concrete-construction. By way of example, for road construction, fine gravel grains are required which contain no more than 20 percent of parts by weight of laminated and pointed grains. As particularly the rocks or stones utilized for road construction by nature break fragmentally or laminated, it is necessary to provide for the comminution by means of gyratory crushers a particular crushing tool for the gyratory crusher.

Crusher tools with concentric teeth disposed on their conical working faces are known and the present invention is an improvement.

The object of the invention is to employ tooth forms which make it possible to produce greater quantities of cubic fine-grains and at the same time to reduce the proportion of finest grain as well as the production of too coarse grain or oversize pieces.

In accordance with the invention, the head cross section of the tooth form is rectangular or trapeze-shaped and has shoulders or curvatures of desired size at the corners, and the surface of the correlated gap has an approximately similar geometrical shape.

Several heads may be disposed on the working faces of the crushing member concentrically to one another on annular or circular lines with diameters increasing toward the base of the cone. A preferred arrangement provides a wide head on the working surface of the crushing ring, to which a correspondingly wider gap is allotted in the working face of the crushing cone.

It was found that with this arrangement, particularly good results are obtained if the crusher gap extending between the working faces of crushing cone and crusher ring is so dimensioned that the crusher space volume toward the base of the cone increases progressively or stepwise. This is attained in accordance with the invention by a corresponding dimensioning of the height of head, of the depth of the correlated gap, and of the distances between the side flanks of head and gap. The same purpose serves also the dimensioning of the width of the gap between conically shaped working surfaces of the crushing cone and the crushing ring on both sides of the tooth. In one embodiment of the tooth form according to the invention, there is provided for the same purpose, that the cutting edge of the head and the cutting edge of the gap correlated with it, in the phase of its greatest mutual approach are parallel to one another or include an acute angle, respectively, at greatly rounded forms according to the cone base converge or diverge. The most favorable course of the contours depends upon the construction measurements of the crushing members, the physical properties of the material to be broken and the static and dynamic forces acting upon the material to be broken. It is provided to make the surfaces of the crushing members subjected to the greatest wear, preferably the tooth edges, of a harder material than the bodies of the crushing members.

The drawings illustrate by way of example an embodiment of a crusher tool according to the invention.

In the drawings:

FIG. 1 shows the crusher arrangement in axial section, and

FIG. 2 shows the interengaging parts of the working faces on a larger scale, likewise in axial section.

Referring to the FIGS. of the drawing, it should be understood that the crushing ring 1 is secured in the machine housing. The crushing cone 2 is so positioned that it may carry out a tumbler movement about the apex of the cone, whereby in cyclic sequence all parts of the working faces during each revolution pass through the phase of greatest mutual approach (as shown to the left in FIG. 1). In FIG. 2 are illustrated more clearly details of a preferred form of tooth construction, likewise in the phase of greatest mutual approach of the working faces. The working faces in the example shown are comprised of upper and lower conical ring surfaces 10 on both sides of a tooth construction, which in axial section has the shape of a broad rectangular tooth, which rises from the downwardly facing face of the crushing ring 1, and whose profile is formed by side flanks 3 and 4 and a broad tooth head surface 9, and to which a tooth gap is correlated in the crushing cone 2, whose profile is limited by its side flanks 5 and 6 and base face 11 and have a geometrical form similar to the tooth 3, 9 and 4. The edges 14 of the profiles of tooth and gap are rounded. The radius of these roundings may be held very small when easily breaking material is to be comminuted. The radius may be selected larger in other cases with advantage as far as the resistance to wear of the tool is concerned. If the radius is selected larger than half the height 16 of the tooth, then the rectangular form of the tooth is changed to a wave-shape, in which the side flanks converge toward the tooth head 9. Similar relations result if a trapezoid is selected as a base shape for the tooth construction.

The desired quality of the broken material is, as a rule, attained with one tooth on the crushing ring 1, but it is also possible to arrange with advantage several teeth or their combination on the crushing ring with concentric prominences and depressions of other cross-sectional form under certain circumstances. An important characteristic of the tool in accordance with the invention consists therein, that the angle of slope of the broken material building up in the phase of the greatest mutual distance of the work faces from the outer flank 5 of the gap prevents definitely the dropping through of too coarse grain or oversize pieces. In this manner, at high weight rate of flow, a retention of the individual particles in the breaking zone is attained, which is sufficient to align once practically all grains of excess size, so that they are grasped directly by the work faces, without it coming to an uncontrollable mutual squeezing into a thickly layered material bed. Also the danger of the briquetting is thereby prevented. There is formed a continuous material bed moving toward the base of the cone. The material is loosened up and constantly turned over in view of the increasing cross section of the breaking gap.

On the edges 14 the remaining flat and elongated pieces of material are broken, so that a great portion of cubic bodies is produced with a decreased portion of fine grain. In order to control the turning over in the material bed in a desired manner, the base line of the gap may be correspondingly formed, preferably so that it forms in the dash-dotted line direction 20 with the cutting edge 9 of the tooth head an acute angle, so that both lines (each according to the type of material to be broken and size of the cone angle) converge or diverge toward the base of the cone. Logically this rule holds good also for curved cutting edges.

In order to take into account the subsequent adjustability of the crushing cone when wear has occurred, it is of advantage when with a new tool the flank distance 13 is made equal to or greater than the flank distance 12 arranged at a higher point toward the cone tip 0. Also the depth 15 of the gap in the crushing cone 2 is selected equal to or greater than the height 16 of the tooth correlated with it. With reference to the wear occurring and the subsequent adjustment necessitated thereby the gap width 18 between the upper cone ring faces 10 in the phase of the greatest approach to the crushing members 1 and 2 is also made equal to or greater than the lower gap width 19.

In the interest of a loose material bed the distance 17 of the head 9 from the surface 11 of the correlated gap in the phase

of its greatest approach should be equal to or greater than the gap widths 18, 19 on both sides of the head. A favorable adjustment is the result when the tooth head surface 9 at a greater approach to the crushing cone 2 enters somewhat in the gap associated with it, as indicated by the dash-dotted lines 7 and 8.

The tooth edges 14, which are subjected to a particular heavy wear may to advantage (for example, by means of a welding operation) be made of a material which is harder than the material of the bodies of the crushing member 1 and 2.

In operation the crusher tools according to the invention have exhibited favorable results for the specific energy consumption and on account of low inner friction in the loosely disposed material bed and also on account of the elimination of the undesirable finest grains a very high degree of efficiency was obtained.

What we claim is:

1. Crusher tool for gyrating crushers, comprising a crushing cone and a crushing ring, each provided with a conical working face, one working face having thereon a concentric annular projection and the other working face having thereon a concentric annular depression, said projection and depression being provided for interengagement with each other, said projection (9) in axial section forming a tooth-profile which is substantially rectangular with rounded corner portions at the edges (14), said depression (11) in the oppositely disposed conical working face forming a tooth gap having in axial section a substantially similar geometrical form as said projection.

2. Crusher tool according to claim 1, in which the depression (11) is arranged in the conical working face of the crushing cone (2) and that the bottom of said depression is wider than the head (9) of the projection in the associated crushing ring (1).

3. Crusher tool according to claim 1, in which the distance (13) between the flank of the tooth-shaped projection (9) and the adjacent flank in the depression (11) near the base of the

crusher cone (2) is at least equal to the same distance (12) between the flanks of this projection and depression disposed closer to the apex of the crushing cone.

4. Crusher tool according to claim 1, in which the depth (15) of the depression (11) in the crushing cone (2) is at least equal to the height (16) of the projection (9) on the crushing ring.

5. Crusher tool according to claim 1, in which the width of the upper gap (18) between the working faces in the phase of 10 the greatest approach of said conical working faces is at least equal to the width of the lower gap (19) between said working faces adjacent the base of the crushing cone.

6. Crusher tool according to claim 3, in which the distance (17) of the outer face of the projection (19) on the crushing ring (1) from the bottom surface of the depression (11) in the crushing cone (2) in the phase of its greatest approach of said working faces is at least equal to the width of the spaces (18, 19) on both sides of the projection (9) in the crushing ring (1).

20 7. Crusher tool according to claim 1, in which the section line (20) extending from the apex of the conical working faces and along the bottom of the depression (11) of the crushing cone (2) and the section line extending along the surface of the projection (9) on the crushing ring (1) in the phase of 25 their greatest approach form an acute angle and converge toward the base of the conical working faces.

8. Crusher tool according to claim 1, in which the section line (20) extending from the apex of the conical working surfaces and along the bottom of the depression (11) of the crushing cone (2) and the section line extending along the surface of the projection (9) on the crushing ring (1) in the phase of 30 their greatest approach form an acute angle and diverge toward the base of the conical working faces.

9. Crusher tool according to claim 1, in which the edges 35 (14) of the projection and depression on the crushing cone and crushing ring consist of a harder metal than the bodies of said crushing cone and crushing ring, respectively.
